UNITED STATES PATENT OFFICE.

JOHN A. RATHBONE, OF DETROIT, MICHIGAN.

CENTRIFUGAL CASTING APPARATUS.

Application filed February 27, 1922. Serial No. 539,415.

To all whom it may concern:

Be it known that I, JOHN A. RATHBONE, a citizen of the United States of America, residing at Detroit, in the county of Wayne and State of Michigan, have invented certain new and useful Improvements in Centrifugal Casting Apparatus, of which the following is a specification, reference being had thereto in the accompanying drawings.

10 The invention relates to apparatus for centrifugally forming castings and consists in various features of construction as hereinafter set forth.

In the drawings:

15 Figure 1 is a sectional elevation of the machine;

Figure 2 is a plan view thereof;

Figure 3 is a vertical longitudinal section in the plane of the axis of the rotary spindle.

20 In the present state of the art annular castings have been formed by the pouring of the molten metal into a revolving mold in which it is distributed by centrifugal action. In order that the castings may be

25 quickly formed and removed, it is desirable to maintain the surface of the mold at a relatively low temperature. This I have accomplished in my improved apparatus by a fluid cooling system in which the cooling

30 medium is held in contact with the metal walls to be cooled by centrifugal action and in which steam or vapor generated is quickly removed. I also make use of the centrifugal action for locking the sections 35 of the mold, so that when the apparatus is stopped, these sections may be easily separated for the removal of the work.

In detail, A is a suitable base which, as shown, is in the form of the tank. B is a standard rising from this base and preferably cast integral therewith, carrying a 40 its upper end a bearing C for a revolving inclined shaft D. There is also a bearing E for the lower end of the shaft and between 45 the bearings C and E there is connected to the shaft a driving mechanism shown as a bevel gear wheel F on the shaft meshing with a driving bevel gear wheel G.

At the upper end of the shaft D is mounted 50 the mold H, preferably by providing the integral flange I upon the shaft, which is bolted or otherwise secured to the body of the mold. The walls and also the base of the mold are hollow and in communication with an axial passage through the shaft D. At the lower end of the shaft there is pro-

vided a suitable water supply connection J having a stuffing box K or other means for connecting it to the revolving part. The water from this connection passes upward 60 into the hollow walls of the mold body and to permit the escape of hot water and steam there is also provided an exit through the axis of the shaft. Preferably this is formed by an inner tube L, which is held in position by a spider M or other suitable means, and at its lower end is in communication with a cross channel N passing out through the walls of the shaft. Thus when water is introduced under pressure, it will flow upward adjacent to the walls of the tube and into the chamber in the mold body, where it is thrown outward by centrifugal action, while the heated water and steam, being of less density, will be forced inward through 70 the axial passage and will eventually escape through the channel N.

For retaining the metal in the mold during the pouring operation, there is provided a removable cover plate O. This is of an 75 annular form and at one side is hinged to the body, as indicated at P, while at its opposite side it is provided with a hooked arm Q engaging a latch or detent R. This latch being pivoted to the body of the mold will 80 be pressed outward by centrifugal action, so that the more rapidly the mold is revolved the firmer the engagement between the latch and the arm. The engaging faces of the latch and the arm are beveled so that the 85 centrifugal pressure will also draw the cover plate tightly against the body of the mold. A light spring S may be provided to initially press the latch outward, but this is not depended upon for locking the parts as the 90 centrifugal pressure will accomplish such result.

With the apparatus as described, in use, the mold being held in inclined position, permits of conveniently pouring the metal therefrom into a ladle or other source of supply. Before pouring, rotary motion is imparted to the shaft and mold and the metal, upon contacting with the walls of the mold, will be set into motion and uniformly distributed. 100 Any excess of metal will flow over the inner margin of the cover plate O, thereby exactly gauging the amount retained for each casting. By reason of the cooling of the mold body, the molten metal is quickly 110 chilled and solidified, so that in a very short time the machine can be stopped and the

casting removed. In removing the casting the cover plate is first turned outward on its hinge, after which the casting can be withdrawn, the shrinkage being sufficient to separate it from the mold body. If desired, the castings may subsequently be subjected to an annealing process to change the character of the metal.

To catch the molten metal which would be thrown off centrifugally in case of the over filling of the mold, I have arranged an annular shield or guard T which completely surrounds the mold without interfering with access thereto. This guard has a notch U cut in the lower portion of the flange thereof adapted to engage the cover plate O when open and thereby to lock the spindle from rotation. This forms a safety device, which insures that the cover plate will be closed before motion is imparted to the machine.

The machine is preferably driven by an electric motor mounted on the base, as indicated at V, and for convenience in controlling this motor the controlling switch W is mounted on the pedestal X within easy reach of the operator. There is also preferably provided a brake for quickly stopping the rotation, this consisting of a lever Y having a brake shoe Y' for engaging the motor shaft and a pedestal Y² for applying braking power thereto.

What I claim as my invention is:

1. An apparatus for centrifugally forming castings, comprising a revoluble annular mold having hollow walls, a hollow shaft on which said mold is mounted, and means for introducing a cooling fluid into said hollow mold through said hollow shaft and for forcing the heated fluid and vapor axially outward through said shaft by centrifugal action.

2. An apparatus for centrifugally forming castings, comprising a revoluble annular mold having hollow walls, a hollow shaft on which said mold is mounted, means for forcing a cooling fluid into said hollow walls through said hollow shaft, and a vent for the escape of heated fluid and vapor communicating with the axis of said hollow shaft, whereby circulation is forced by centrifugal action.

3. An apparatus for centrifugally forming castings, comprising an inclined hollow rotary shaft, an annular mold having hollow walls mounted on said shaft, means for forcing a cooling liquid into said hollow walls through said hollow shaft, a vent tube arranged axially within said hollow shaft, communicating at its lower end with a transversely extending escape port, whereby the heated fluid and vapor will be forced outward centrifugally through said vent tube and escape port.

4. An apparatus for centrifugally form-

ing castings, comprising a rotary mold, a cover plate therefor, a latch for holding said cover plate forced outward by centrifugal action, and coacting cam surfaces on said latch and cover plate by which the centrifugal pressure will press the cover against the body of the mold.

5. An apparatus for centrifugally forming castings, comprising an inclined rotary hollow shaft, an annular mold mounted on said shaft and having hollow walls in communication with the same, means for introducing a cooling fluid through said hollow shaft and into the hollow walls of said mold, and an annular cover plate for said mold through the open center of which the molten metal may be poured into contact with the chilled walls of the mold.

6. An apparatus for centrifugally forming castings, comprising an inclined rotary shaft, a mold mounted on said shaft, an annular cover plate for said mold permitting the pouring of the molten metal therein and retaining the metal required for the casting while permitting overflow of an excess of metal, and an annular shield surrounding said mold for catching the excess metal when thrown out centrifugally from the mold.

7. An apparatus for centrifugally forming castings, comprising an inclined rotary shaft, a mold mounted on said shaft, a hinged annular cover plate for said mold permitting the pouring of the molten metal thereinto and retaining the metal for the casting while permitting overflow of excess metal, a latch for holding said cover plate locked when the mold is revolving, an annular shield surrounding said mold for catching the overflow of molten metal thrown out centrifugally, and means for forming an interlocking engagement between said cover plate and mold when the former is open to prevent the imparting of rotary motion to the mold.

8. An apparatus for centrifugally forming castings, comprising a revoluble annular mold having hollow walls, a hollow shaft on which said mold is mounted, means for introducing a cooling fluid into said hollow mold through said hollow shaft and for forcing the heated fluid axially outward through said shaft.

9. An apparatus for centrifugally forming castings, comprising a revoluble annular mold having hollow walls, a hollow shaft on which said mold is mounted, means for introducing a cooling fluid into said hollow mold through said hollow shaft, and a tube within said hollow shaft for withdrawing the heated fluid, said tube communicating with said mold substantially at the axis thereof.

10. An apparatus for centrifugally forming castings, comprising a rotary mold, a

cover plate therefor, provided with a cam surface, and a latch having a cooperating cam surface in engagement with said first mentioned cam surface whereby the cover is pressed against said mold through centrifugal action.

11. An apparatus for centrifugally forming castings, comprising a rotary mold, a cover plate therefor, a spring pressed latch for removably holding said cover plate to said mold when the latter is stationary, and coacting cam surfaces for pressing the cover to said mold by centrifugal action when the mold is rotating.

12. An apparatus for centrifugally forming castings, comprising a rotary mold, a cover plate therefor, provided with a cam surface, a latch pivotally secured to said mold, a cooperating cam surface on said latch engageable with the cam surface on said cover whereby the latter is pressed to said mold through centrifugal action of said latch, and a spring for removably engaging the latch with said cover when the apparatus is stationary.

In testimony whereof I affix my signature.

JOHN A. RATHBONE.
